HUMIDIFIER

James W. Galloway, Cedar Falls, Iowa, assignor to
 The Automatic Humidifier Company, Cedar
 Falls, Iowa

Application May 3, 1937, Serial No. 140,405

2 Claims. (Cl. 126—113)

My invention relates to improvements in furnace humidifier installations, and an object of my improvements is to furnish different means for removably and separately mounting a humidifier pan and accompanying trough and thermostat within the hot air jacket of a furnace.

Another object of my improvements is to combine with the furnace and its apertured jacket, a hand-hole plate adapted to be secured over the jacket aperture, and a gate member slidably and removably mounted upon the hand-hole plate, operable when the gate is in opened position to be manually lifted and supported in its lifted condition to permit the humidifier pan and also the thermostat and trough accompanying it to be inserted into or removed from the jacket when necessary.

Another object of my improvements is to provide the hand-hole plate with an aperture to removably receive an end projection of the humidifier pan to support the pan within and across the jacket in a suitable position.

I have accomplished these objects by the means which are hereinafter described, claimed and illustrated in the appended drawing.

It is to be understood, that various specific changes in the forms and connections of said devices may be made without departing from this invention or the scope of the claims.

Fig. 1 is a front elevation of the upper end of a hot air furnace having parts of the front and side walls broken away to show the mounting of a humidifier and associated thermostat therein. Fig. 2 is an enlarged elevation of the hand-hole plate with the gate member mounted movably thereon.

1 is the upper part of a hot air furnace above the fire-box crown 26. 12 is an open top pan horizontally supported across the interior of the jacket above the crown 26. 13 is an overflow pipe traversing the jacket with its inner end loosely seated in the casing 1, to maintain it level horizontally, and 14 is a wedge-shaped bracket, projecting horizontally outwardly from the opposite end of the pan, with down bent termination 16 in the pan and secured thereto by bolts 15 connecting it to the flange 12.

The furnace jacket 1 has an aperture of sufficient size and proper shape, and, referring to Fig. 2, a substantially rectangular plate 2 is mounted about and over this aperture exteriorly of the jacket and secured removably by screws or other fastening means traversing the holes 3. The plate 2 has a depending part 8 having a medial horizontal slot 9 registering with a similar slot

in the jacket 1. The bracket 14 on the pan 12 extends outwardly through said slot wedgingly, securing the pan removably upon and inside the jacket.

The plate 2 has a relatively large substantially rectangular opening 5 including a notch 10 below. At opposite sides the plate 2 has horizontally alined fixed pins 4 to traverse vertically disposed slots 7 in the opposite end parts of a gate or slide plate 11 positioned to move vertically upon the outer face of the plate 2 and covering the aperture 5 thereof when the plate 11 is in a lowered position. These pins 4 are headed at 6 with a wider diameter than the width of the slots 7. At upper and lower circular ends the slots 7 are wider than the heads of the pins 4. The plate 11 is shown in its lowered position with the upper wider ends of the slots traversed by the pins 4, and the plate 11 then closes the aperture 5 of the plate 2. The plate 11 may be manually lifted to a position where the heads 6 of the pins 4 may be in the lower wider ends of the slots 7, and as the pin heads are of less diameter than the said wider ends, the plate 11 may be disengaged from the pins. Then the trough 18 with thermostat 17 mounted therein may be removed outwardly by lifting them and then passing them outwardly through the aperture or hand-hole 5. Also, the pan 12 may be pushed rearwardly slidably upon the loosely connected pipe 13, until cleared from the slots at 9 in the jacket 1 and plate extension 8, and the pan then removed by way of the aperture 5. The thermostat 17 is not claimed specifically herein, but may have as operating parts a bolt 20 to clamp the device to the jacket on the inside, an element of the thermostat having outside valvular and other elements such as supply pipe 11, a valve chamber 22, spring 23 variably tensioned by a nut 24, and a pressure plate 21. The thermostat is secured in and above the trough 18 by screws 19.

I claim:

1. In a hot air furnace, a jacketed hot air distributing chamber having a relatively large side wall aperture, a plate having a relatively small aperture in its lower part and a larger aperture thereabove and the plate being secured across said wall aperture, a second plate vertically slidable upon and removably mounted across the first plate and its larger aperture, an open pan in said chamber having an inwardly removable wedge-shaped bracket member seated in said small aperture, and a water delivery trough and thermostat traversing the larger aperture in the first plate.

2. In a hot air furnace, a jacketed hot air distributing chamber having a wall aperture, an apertured plate with lower edge part notched and secured removably across said wall aperture,
5 a supply trough traversing the notch of said apertured plate, a slidable closure plate movably mounted across all but the notch of the aperture of the first plate, an open top evaporating pan positioned within and across said chamber and having an end bracket fixed there-

on, the first plate having a slot for removably seating said bracket therein, a thermostat within said chamber and mounted on said trough and including adjusting means for the thermostat positioned exteriorly of the chamber, and said 5 trough and thermostat and pan being separately removable outwardly from the chamber by way of the aperture in the first plate.

JAMES W. GALLOWAY. 10
